ABSTRACT OF THE DISCLOSURE

For the removal of a spring pin from a blind hole, an internal protrusion in the spring pin and an extraction tool having a shank shaped to be inserted past the protrusion and, after rotation of the shank, to engage the protrusion, and a nut threadedly engaging the larger diameter main body of the extraction tool so that the nut may be screwed against the outer surface of the member into which the spring pin is inserted to withdraw the spring pin into the nut.

This invention relates to means for extracting spring pins from blind holes.

Spring pins—that is, longitudinally slotted cylindrical tubular members—are used in many diverse applications, for example as wrist pins, hinge pins, pivots, assembly fasteners, stop pins, locator pins, etc. In many of these applications, the spring pins are inserted in blind holes—i.e., holes open at only one end. It is frequently desired to remove the spring pins, for example, for disassembly of the mechanism for cleaning, repair or adjustment. In blind hole installations, where the spring pin is fully inserted, so that it does not project beyond the outer surface of the member into which it is inserted, such removal has proved extremely difficult. In many instances, it has been necessary to drill out the spring pin, or to drill a hole through the member from the opposite side to permit insertion of a punch to engage the inner end of the spring pin so that it may be hammered out. Such expedients not only require substantial time and effort, but either destroy the spring pin or damage the member from which it is removed.

It is therefore among the objects of the present invention to provide means enabling quick and easy removal of a spring pin from a blind hole without damage either to the spring pin or to the member in which it is mounted.

Another object is that of providing a spring pin extracting tool which is simple and economical in construction and practical and convenient in operation.

Another object is that of providing a spring pin having means engageable by an extracting tool, said means being of such nature that they may be provided in a conventional spring pin without substantial increase of its cost of manufacture and without preventing any normal use of the spring pin or in any way impairing its efficacy.

The spring pin shown in FIG. 1 comprises a cylindrical tube 10 having a longitudinal slot 12 therein and is provided with a pair of centrally located opposed indentations 14 forming in the sidewall of its bore a pair of opposed internal protrusions 14'.

In FIG. 2, the spring pin is shown installed in a blind hole 16 in a member 18, with its outer end substantially flush with the adjacent outer surface 18a of the member 18. The extraction tool, generally designated 20, is shown in the process of being inserted into the spring pin 10 preparatory to its removal from the blind hole 16.

The extraction tool 20 includes a body portion 22 which is externally threaded, with the root diameter of the thread exceeding the outside diameter of the spring pin. Extending coaxially from the inner end 22a of the body portion

2

22 is a cylindrical shank 24 whose diameter is slightly less than the inside diameter of the spring pin. The shank is provided at its inner end with a head portion 26 which is provided with a pair of opposed flats 26a which are cut to such depth that when the tool is rotated to the inserting position shown in FIG. 2, at which these flats are opposite the internal protrusions 14' in the spring pin, the head 26 will not engage the protrusions during insertion of the shank of the tool into the bore of the spring pin. The shank is of such length that when it is fully inserted into the spring pin, as shown in FIGS. 2 and 3, the head 26 is beyond the protrusions 14' so that the tool may be rotated to the withdrawing position shown in FIG. 3, in which the head portion 26 is engaged behind the protrusions 14' in position to exert a withdrawing force on the spring pin.

The head portion 26 is connected to the shank 24 by a neck portion 28 which is of reduced diameter to clear the internal protrusions 14' and permit free rotation of the tool between the aforementioned two positions. The neck portion 28 is located so that it is opposite the protrusions 14' when the shank is fully inserted into the spring pin 10 with the inner end 22a of the body portion 22 in abutment with the outer face 18a of the member 18, so that no care is required in positioning the neck portion opposite the protrusions 14'.

As shown in FIG. 3, a withdrawing force is exerted on the tool by a nut 30 which is threaded onto the body portion 22 and against the outer surface 18a of the member 18. As the nut 30 is screwed further in the direction of the member 18, the body portion 22 and shank 24 are drawn outwardly, withdrawing the spring pin 10 from the hole 16, with at least the outer end of the spring pin moving into the bore of the nut 30, which is made possible by the fact that the crest diameter of the nut thread 32 exceeds the outside diameter of the spring pin 10.

It will therefore be appreciated that the present invention accomplishes all of the aforementioned and other apparent desirable objectives. However, it should be emphasized that the particular embodiment of the invention described herein and shown in the drawing is intended as merely illustrative of the principles of the invention and not as restrictive of its scope, which is defined only by the appended claims. It will be readily apparent to those skilled in the art that various modifications may be made in the illustrative embodiment shown and described without departing from the principles of the invention. For example, either a greater or a lesser number of internal protrusions may be provided in the spring pin so long as they are circumferentially spaced to permit insertion of the head portion of the extraction tool, which of course should be provided with at least an equal number of similarly spaced relieved portions. However, a plurality of symmetrically spaced protrusions are preferred, so that the withdrawing force applied to the spring pin will be balanced about the axis of the spring pin to prevent cocking of the spring pin in the hole and enable its removal from the hole within a minimum of applied force.

I claim:

1. The combination of a spring pin having extraction means with an extraction tool engageable therewith, said spring pin comprising a longitudinally slotted cylindrical tubular body having in the sidewall of its bore a circumferentially discontinuous internal protrusion, said extraction tool having a shank of such diameter and length as to extend into said bore to a depth beyond said protrusion, with a head portion at the outer end of said shank so shaped that, in one position of axial rotation of said shank, said head can move into said bore past protrusion and, in another position of axial rotation of said shank, said head engages said protrusion to transmit a with-

drawing force to said spring pin, and a neck portion connecting said head portion to said shank, said neck portion being of reduced cross section to provide clearance opposite said protrusion for axial rotation of said shank between said two positions.

2. The combination as described in claim 1 in which said spring pin has a plurality of symmetrically spaced internal protrusions and the head portion of said extraction tool is provided with an equal number of equally spaced relieved portions to clear said protrusions in certain positions of axial rotation of said extraction tool.

3. The combination as claimed in claim 2 wherein said spring pin is provided with two diametrically opposed internal protrusions and said relieved portions comprise opposed flats.

4. The combination of a spring pin having extraction means with an extraction tool engageable therewith, said spring pin comprising a longitudinally slotted cylindrical tubular body having in the sidewall of its bore a circumferentially discontinuous internal protrusion, said extraction tool having a body portion with a shoulder thereon adapted to abut the outer surface of a member having therein a cylindrical hole in which said spring pin is received with its outer end substantially flush with said outer surface, and a shank projecting perpendicularly from said shoulder, the diameter and length of said shank permitting its insertion into said bore to a depth beyond said protrusion, with a head portion at the outer end of said shank so shaped that, in one position of axial rotation of said shank, said head can move into said bore past said protrusion and, in another position of axial rotation of said shank, said head engages said protrusion to transmit a withdrawing force to said spring pin, a neck portion connecting said head portion to said shank, said neck being so located as to be opposite said protrusion when said shoulder is abutted with said outer surface and being of reduced cross section to provide clearance opposite said protrusion for axial rotation of said shank between said two positions.

5. The combination of a spring pin having extraction means with an extraction tool engageable therewith, said spring pin comprising a longitudinally slotted cylindrical tubular body having in the sidewall of its bore a circumferentially discontinuous internal protrusion, said extraction tool having a shank of such diameter and length as to extend into said bore to a depth beyond said protrusion, with a head portion at the outer end of said shank so shaped that, in one position of axial rotation of said shank, said head can move into said bore past said protrusion and, in another position of axial rotation of said shank, said head engages said protrusion to transmit a withdrawing force to said spring pin, a neck portion connecting said head portion to said shank, said neck portion being of reduced cross section to provide clearance opposite said protrusion for axial rotation of said shank between said two positions, said extraction tool also

having a cylindrical body portion extending axially from said shank and being externally threaded for threaded engagement with an internally threaded nut which may be screwed onto said body and into engagement with the outer surface of a member in which said spring pin is received to exert a withdrawing force on said spring pin, with the inside diameter of said nut exceeding the outside diameter of said spring pin to permit movement of said spring pin into said nut as said spring pin is withdrawn.

6. The combination of a spring pin having extraction means with an extraction tool engageable therewith, said spring pin comprising a longitudinally slotted cylindrical tubular body having in the sidewall of its bore a circumferentially discontinuous internal protrusion, said extraction tool having a body portion with a shoulder thereon adapted to abut the outer surface of a member having therein a cylindrical hole in which said spring pin is received with its outer end substantially flush with said outer surface, and a shank projecting perpendicularly from said shoulder, the diameter and length of said shank permitting its insertion into said bore to a depth beyond said protrusion, with a head portion at the outer end of said shank so shaped that, in one position of axial rotation of said shank, said head can move into said bore past said protrusion and, in another position of axial rotation of said shank, said head engages said protrusion to transmit a withdrawing force to said spring pin, a neck portion connecting said head portion to said shank, said neck being so located as to be opposite said protrusion when said shoulder is abutted with said outer surface and being of reduced cross section to provide clearance opposite said protrusion for axial rotation of said shank between said two positions, said body portion being externally threaded, and an internally threaded nut threadedly engaging said body portion, the crest diameter of the threaded surface of said nut exceeding the outside diameter of said spring pin, whereby said nut may be screwed against said outer surface to exert a withdrawing force on said spring pin, with said spring pin moving outwardly into said nut as said spring pin is withdrawn.
